UNITED STATES PATENT OFFICE

154,472

DESIGN FOR A SHELF FOR EYEGLASSES

Vincent Giuliana, Springfield, Mass.

Application September 8, 1947, Serial No. 141,268

Term of patent 3½ years

(Cl. D57—1)

To all whom it may concern:

Be it known that I, Vincent Giuliana, a citizen of the United States, residing at Springfield, in the county of Hampden and Commonwealth of Massachusetts, have invented a new, original, and ornamental Design for a Shelf for Eyeglasses, of which the following is a specification, reference being had to the accompanying drawings forming part hereof:

Fig. 1 is a plan view of a shelf for eyeglasses showing my new design;

Fig. 2 is a front elevational view of the shelf for eyeglasses shown in Fig. 1;

Fig. 3 is a side elevational view of the shelf for eyeglasses shown in Figs. 1 and 2; and

Fig. 4 is a rear elevational view of the same.

I claim:

The ornamental design for a shelf for eyeglasses, as shown.

VINCENT GIULIANA.
